ELEVATOR CONTROL SYSTEM

Charles G. Wallis, Chicago, Ill., assignor to Westinghouse Electric Elevator Company, a corporation of Illinois

Application February 18, 1932. Serial No. 593,780

16 Claims. (Cl. 187—29)

My invention relates to automatically operated electric elevator systems adapted for operation without a skilled attendant, and relates particularly to automatic elevator control systems for effecting a substantially immediate response to a call registered while the car is proceeding to a predetermined position under the influence of a biasing control which is effective when no calls are registered.

10 In some buildings, such as apartment houses, hotels and the like, elevator service is often of such intermittent character as to render the cost of an attendant prohibitive. Elevator systems have been devised for the purpose of permitting 15 the operation of the elevator by unskilled persons, such as the tenants of an apartment house, whereby the presence of an attendant in the car at all times is unnecessary.

In one of the elevator control systems devised, 20 the car remains at the floor corresponding to the last call registered until another call is registered. This type of elevator control system has the disadvantage of causing the elevator car to move from a remote floor to the floor at 25 which a subsequent call is registered and thus necessitates an appreciable delay in calling the car to the floor at which the call is registered.

In order to reduce the time required for the 30 elevator car to move to a floor at which a call is registered, elevator control systems have been devised, embodying a so-called "biasing" control, for causing the elevator car to automatically move to a predetermined position, such as 35 the lower terminal floor or a floor intermediate of the lower and upper floors, after the complete response to a prior call. In elevator control systems of this type, however, it is necessary that the elevator car proceed to the predetermined 40 position without stopping, once it has started to that position, except that if a call is registered in advance of the car and for the same direction of movement as that in which the car is moving, the car will stop. The result of this 45 feature is that calls behind the elevator car or calls in advance of the car which require an opposite direction of movement in response thereto than that in which the car is moving, when registered while the car is proceeding to 50 the predetermined position, are not responded to until the elevator car reaches the predetermined position. Thus, the elevator car frequently passes the floor at which a call is registered and returns thereto only after having 55 reached the predetermined position. Obviously,

this causes an unnecessary delay in responding to a registered call.

In elevator control systems of the type comprising my present invention, this disadvantageous feature is eliminated because a substantially immediate response to a call is effected thereby, without the necessity of the car proceeding to the predetermined position. For example, if an up call is registered on the third floor of a ten-story structure when the car is at the eighth floor 60 descending toward the first or lower terminal floor, under the influence of the biasing control, the car is caused to stop at the third floor upon attaining that level instead of proceeding to the first floor and then returning to the third floor. 65 As another example, let it be supposed that a "down" call is registered at the eighth floor of a ten-story structure when the car is at the fifth floor descending toward the first or lower terminal floor under the influence of the biasing 70 control. In such case, the car will stop at the nearest floor possible in the direction it is moving, (in the case given this being the fourth floor), reverse its direction of movement and ascend to the eighth floor, where it automatically 75 stops.

It is, therefore, an object of my invention to effect the most efficient method of operating an elevator system of the type herein described.

Another object of my invention is to effect 85 with the minimum of delay, a response to a call registered.

Another object of my invention is to provide a novel control system for effecting a so-called "biasing" control of an elevator car whereby 90 it is caused to move automatically to one predetermined position, or, optionally, to any one of a plurality of predetermined positions, after it has completely responded to the last call registered. 95

A further object of my invention is to effect a response of an elevator car to a registered call, regardless of the location of the call with respect to the car, in preference to a response of the car to a "biasing" control means influencing 100 the elevator car to a predetermined position.

Other objects of my invention will be apparent from the following description of my invention when taken in connection with the accompanying drawings wherein:

Figures 1, 2 and 3, taken together, constitute an across-the-line diagram illustrating one embodiment of my invention.

Fig. 4 is a diagram, showing an elevator car provided with inductor slow-down and stopping 110

relays and the relative positions, with respect to several floors, of inductor plates therefor mounted in the hatchway and adapted to cooperate with the inductor relays on the elevator car.

5 Fig. 5 is a diagram illustrating the operation of any of the inductor relays shown in Figs. 1 and 4, and

10 Fig. 6 is a diagram showing the position of the movable contact members on the floor selector, employed in my invention, with respect to the stationary segments thereof, at any one time, and the corresponding positions of inductor plates mounted in the hatchway.

15 Referring to Figs. 1, 2, 3 and 4, the control system embodying my invention is illustrated as applied to a building having a basement floor B and four other floors, designated as #1, #2, #3, and #4, respectively. It should be understood, however, that the number of floors in the 20 building is immaterial and that my invention can be embodied in a control system applicable to any building, regardless of the number of floors therein.

25 The control system, constituted by Figs. 1, 2 and 3, includes a "variable-voltage" or Ward-Leonard type of motor control, which comprises an elevator motor M, of a direct current type, provided with a separately excited field-winding MF, which motor is employed for driving the 30 elevator car C, shown in Fig. 4. A cable drum D, secured to the shaft of the armature MA of the motor M, is adapted to support a cable Ca which is wrapped therearound in the usual manner, the cable being secured at one end 35 thereof to the car C and at the other end thereof to a counter-weight Cw.

40 A brake B, of well known construction, is provided for the motor M and includes a brake drum BD which is preferably secured to the shaft of the motor armature MA and a brake shoe BS which is adapted to frictionally engage the drum under the influence of a biasing means, such as a compression spring, not shown. In accordance with well known practice, a brake 45 coil or solenoid BC is also provided for actuating a plunger member of the brake shoe BS and thereby releasing the brake when the coil is energized.

50 Power is supplied to the winding of the armature MA of the motor M from a generator G, the winding of the armature GA of the generator being connected in loop circuit with the winding of the armature MA and a series field winding GSF of the generator G.

55 The generator armature GA is driven by a motor DM of any suitable type, such as the three-phase induction motor illustrated, which is connected to the three-phase supply conductors m, n, o, by means of a switch 3.

60 The generator G is provided with a separately excited field-winding GF which is reversibly controlled by an "up" direction relay or switch 1 and a "down" direction relay or switch 2, reversible control for the motor M being thereby, 65 also effected.

70 Resistors R1 and R2 are connected, in series with generator field-winding GF, across the supply conductors L1 and L2 and are adapted to be short-circuited by the contact members of relays GR5 and GR6, respectively, whereby acceleration of the motor M is effected. Obviously, the relays GR5 and GR6 are employed to reinsert the resistors R1 and R2 to effect deceleration of the motor M.

75 A relay 6 is employed in conjunction with

certain contact members a of either relay 1 or 2 for effecting the energization of the brake coil BC and also the coil of a relay 39.

80 Relay 39 is actuatable to partially complete a circuit for effecting the energization of coils 3L, 2L and 1L of high-speed slow-down inductor relay H, intermediate-speed slow-down inductor relay I and stopping inductor relay S, respectively.

85 The inductor relays H, I and S may be of any suitable type but are preferably of the type described in the copending application of Harold W. Williams, Serial No. 279,771, filed May 22, 1928 and assigned to the Westinghouse Electric & Manufacturing Company, the construction and 90 operation of which may best be understood by reference to Fig. 5 in which one is diagrammatically shown.

95 Referring to Fig. 5, any of the inductor relays, as, for example, the inductor relay H, comprises a magnetic structure Ha of T-shape, having a central core portion Hb and a pair of small lugs or projections Hc extending from the ends thereof on opposite sides. A pair of armatures Hu and Hd, of magnetic material are pivoted to the 100 magnetic structure Ha in juxtaposition to the lugs Hc. Each of the armatures Hu and Hd is provided with a contact member for engaging a separate stationary contact member. The contact member on armature Hu and its associated stationary contact member will herein-after be designated as contact members UH and the contact member on armature Hd with its associated stationary contact member will be designated as contact members DH. 105

110 The armatures Hu and Hd are biased by any suitable means, such as a spring, to a position in which their contact members respectively engage their associated stationary contact members. When an armature is pivoted away from its associated stationary contact member, the switch constituted thereby is opened.

115 The energizing coil 3L for relay H is mounted on the core portion Hb of the magnetic structure Ha. The magnetic structure Ha and the 120 armatures Hu and Hd constitute a divided magnetic circuit of two branches both of which are normally incomplete because of the large air gaps between the upper portion of the magnetic structure and the armatures. 125

130 The inductor relays I and S are provided with contact members UI and US, respectively, which correspond to contact members UH of relay H and are also provided with contact members DI and DS, respectively, which corresponds to contact members DH of relay H.

135 The energizing windings for relays I and S are designated respectively as 2L and 1L.

140 The operation of any of the inductor relays is as follows, relay H being taken as an example. As long as the winding 3L is de-energized, the armatures Hu and Hd remain in their biased positions with their contact members engaging their respectively associated stationary contact members. Upon the energization of the winding 145 3L, as by the closure of a switch 3S connecting the winding to a suitable source of energy such as the battery 3B, a magneto-motive force is impressed upon the magnetic circuit of the relay. Because of the large air gaps between the armatures and the opposite ends of the magnetic structure Ha, the magnetic flux set up in the relay is insufficient to cause a pivotal movement of the armatures.

150 If a branch of the magnetic circuit is com-

pleted, however, as by movement of the relay into a position adjacent to an inductor plate 1HU, the corresponding armature H_u pivots, against the force exerted by the biasing means, 5 into a position to engage the corresponding lug H_c , thus effecting the disengagement of the contact members UH . As the relay passes the inductor plate and moves away therefrom, the armature H_u does not return to its biased position 10 because of the magnetic attraction exerted thereon by the lug H_c with which it is associated and thus the contact members UH remain open.

In a similar manner, assuming the coil 3L to be energized, and the second branch of the magnetic circuit to be completed by the movement of the relay into the position adjacent another inductor plate 1HD, the armature H_d is pivoted into a position in engagement with its corresponding lug H_c thus effecting the opening of 20 contact members DH . When the relay moves away from the inductor plate the armature H_d does not return to its biased position because of the magnetic attraction exerted thereon by the lug H_c with which it is in engagement and thus 25 the contact members DH remain open.

When the winding 3L is deenergized by opening the switch 3S, the magnetic attraction exerted upon the armatures H_u and H_d by the lugs H_c , is not sufficient to overcome the force 30 exerted thereon by the biasing means and the armatures are returned to their biased positions. Thus contact members UH and DH are reclosed.

If the winding 3L of the relay is deenergized, 35 a movement of the relay to a position adjacent an inductor plate is not effective to cause a separation of the contact members UH or DH . It will, therefore, be seen that a separation of the contact members UH and DH is effected 40 only when the winding 3L is energized and the relay is moved into a position adjacent a corresponding inductor plate.

Referring to Fig. 4, the relative disposition of the inductor plates for effecting the slow- 45 down and stopping of the elevator car C at floors #1 and #2 are diagrammatically shown. It should be understood that the position of the inductor relays H, I and S on the elevator car is immaterial and that while they are illustrated 50 in Fig. 4 as being in alignment at the top of the elevator car, thus necessitating the disposition of the stopping plate 1SU a distance above the floor #1 corresponding to the distance of the inductor relays from the floor of 55 the elevator car, any other disposition of the inductor relays may be had with a corresponding adjustment in the position of the inductor plates.

Assuming the elevator car to be ascending 60 toward floor #1 it will be clear that the contact members UH , UI and US are opened in succession by the relays H, I and S reaching the level of their respectively associated inductor plates 1HU, 1IU and 1SU.

In a similar manner when the elevator car is descending toward floor #1 contact members 65 DH , DI and DS are opened in succession by the relays H, I and S successively reaching the level of the inductor plates 1HD, 1ID and 1SD with which they are respectively associated.

The energization of the energizing coils 3L, 70 2L and 1L of relays H, I and S, respectively, is effected in a manner which will be described in detail hereinafter.

Referring to Fig. 6, all of the inductor plates

for all of the floors are diagrammatically illustrated, the "up" high-speed plates for floors #1, #2, #3 and #4 being designated 1HU, 2HU, 3HU and 4HU, respectively; the "up" intermediate-speed plates for the same floors being designated 1IU, 2IU, 3IU and 4IU, respectively; and the "up" stop-plates for the same floors being designated 1SU, 2SU, 3SU and 4SU, respectively. Similarly, the "down" high-speed plates for the basement floor B and floors #1, #2 and #3 are designated, respectively, BHD, 1HD, 2HD and 3HD; the "down" intermediate-speed plates for the same floors are designated, respectively, BID, 1ID, 2ID, and 3ID; and the "down" stop-plates for the same floors are designated, respectively, BSD, 1SD, 2SD and 3SD. For purposes of clarity, the groups of "up" and "down" plates for the various floors have been moved laterally apart and are not shown in their proper relative vertical relation as in Fig. 4.

It will be noted that whereas in Fig. 4, the stopping plates 1SU, 2SU, etc., are disposed in the hatchway some distance above the level of the floor to which they correspond, for reasons 100 as previously explained, in Fig. 6 the same plates are illustrated as coinciding with broken lines passing therethrough.

These broken lines are, respectively, the "inductor floor lines" corresponding to the various floors, the inductor floor lines being a distance above the floor, to which each corresponds, which is equal to the distance of the inductor relays on the car above the floor of the elevator car.

Referring to Figs. 1, 2 and 3 a safety circuit including a top over-travel switch, a bottom over-travel switch, a plank switch, a governor switch and a motor-generator over-speed switch, all illustrated symbolically by characters X is provided in series with an emergency stop switch suitably identified in Fig. 1 for preventing the energization of each of the relays 1, 2 and 6 unless all of the switches are closed.

A relay 42 is employed for completing a circuit for energizing the relays 1, 2 and 6 in a manner which will be hereinafter fully described.

A voltage-responsive relay 31, of well known construction is provided with an actuating coil 125 which is connected across the brush terminals of the winding of the armature MA and effects the energization of the relay GR6 to short circuit the resistor R2 and thereby effect the acceleration of the motor to high speed.

The "up" contact members UH and "down" contact members DH of the high-speed inductor relay H, when opened in the manner previously described, effect the deenergization of the coil of relay GR6 which results in the deceleration of the elevator car to intermediate speed.

The "up" contact members UI and the "down" contact members DI of intermediate speed inductor relay I when opened, as previously described, effect the deenergization of relay GR5 which results in a deceleration of the elevator car to slow speed.

The "up" contact members US and the "down" contact members DS of stopping inductor relay 140 S when opened, as previously described, effect the deenergization respectively of relays 1 and 6 and 2 and 6 which results in the final stopping of the elevator car.

Any suitable type of operating means for the 150

elevator car may be employed in conjunction with my invention. However, as illustrated, in Figs. 2 and 3, I prefer to employ call-means consisting of an "up" and a "down" push-button switch at each floor except the upper and lower floors, namely, floor #4 and the basement floor, at which are disposed only a "down" push-button and an "up" push-button, respectively. Obviously, the elevator car never rises above the upper terminal floor and never descends below the basement floor. Therefore an "up" push-button at the upper terminal and a "down" button at the basement floor would be superfluous and unnecessary.

15 I prefer also to employ additional call-means consisting of a plurality of push-button switches in the elevator car, one for each of the floors past which the elevator car moves and at which it may stop.

20 The push-button switch at the upper terminal or fourth floor is designated, in Fig. 2, as 4D and the push-button switch at the basement floor is designated as BU. The "up" direction push-button switches at floors #1, #2 and #3 are designated, in Figs. 2 and 3, as 1U, 2U, and 3U, respectively. The "down" direction push-button switches at floors #1, #2 and #3 are designated as 1D, 2D, and 3D, respectively.

25 The push-button switches in the elevator car are designated BC, 1C, 2C, 3C, and 4C, corresponding, respectively, to the basement floor and floors #1, #2, #3 and #4.

30 A plurality of relays or switches 2B, 11, 12, 13, 14, 21, 22 and 23 are provided for registering calls in response to the operation of the push-button switches at the floors and in the car, which relays will hereinafter be termed call-registering or call-registration relays.

35 The "two-digit" designations for these relays are significant of their function and character. The first digit "1" or "2" indicates that the relay registers an "up" or a "down" call, respectively. The second digit, namely "B", "1", "2", "3" or "4", designates the floor to which the relay corresponds. For example, relay 13 registers an "up" call in response to the operation of push-button switch 3U at floor #3.

40 The upper terminal floor, which in this case is the fourth floor, has but one relay, 14, associated with the push-button switches 4D and 4C and the basement floor has but one relay 2B associated with the push-button switches BC and BU.

45 A pair of relays 11 and 21 are associated, respectively, with the "up" and "down" direction push-button switches 1U and 1D at floor #1.

50 A pair of relays 12 and 22 are associated, respectively, with the "up" direction switch 2U and the "down" direction switch 2D at floor #2.

55 A pair of relays 13 and 23 are associated respectively, with the "up" direction switch 3U and the "down" direction switch 3D at floor #3.

60 It is to be noted that the push-button switches 4D and BU at the upper floor and basement floor, respectively, are so designated merely to conform to the desire of the passenger to go down or up respectively, but that actually, 4D is the equivalent of an "up-call" push button and BU is the equivalent of a "down-call" push button.

65 The push-button switches 1C, 2C and 3C in the elevator car are adapted to be operatively associated with both of the relays which are associated, individually with the corresponding push-button switches at the corresponding floor.

Each of the relays 2B, 11, 12, 13, 14, 21, 22 and 23 is provided with a main coil for actuating the relay and a neutralizing coil for de-actuating the relay, the coils being designated by characters consisting of the numeral designating the relay and a suffix M or N, respectively. For example, the main coil of relay 14 is designated as 14M and the neutralizing coil for relay 14 is designated as 14N.

70 Taking the push-button switches and relays for the third floor as an example, the operation of push-button switch 3U closes a circuit for energizing the main coil 13M for coil 13. The normally open contact members *a* of relay 13, when closed as a result of the energization of the main coil 13M, establish a holding circuit which shunts the push-button switch 3U, and thus permits the latter to be released and the call so registered maintained.

75 Similarly, the operation of the push-button switch 3D closes a circuit for energizing the main coil 23M of relay 23, a holding circuit being established therefor by contact members *a* of relay 23 which close when the main coil 23M is energized.

80 The push-button switch 3C in the car is provided with a pair of contact members connected respectively to the main coils 13M and 23M and a common contact member connected to the supply conductor L1, whereby upon the operation 105 of the switch both of the coils 13M and 23M are energized. I provide additional means, which will be hereinafter described, for selecting which of the relays will be effective to control the subsequent direction of movement of the elevator car.

85 A floor selector FS is provided which may be of any suitable construction and which functions in a manner which will be hereinafter described in detail. The floor selector FS is provided with an "up" cancellation contact segment and a "down" cancellation contact segment for each of the floors except the basement and the upper terminal floor, for each of which is provided only a "down" cancellation segment and an "up" cancellation segment, respectively. The "up" segments 1CU, 2CU, 3CU and 4CU disposed relatively in positions corresponding to the position of the elevator car at floors #1, #2, #3 and #4, respectively, comprise one row, and the "down" segments BCD, 1CD, 2CD and 3CD disposed relatively in positions corresponding to the position of the elevator car at the basement floor, floors #1, #2, and #3, respectively, comprise an adjacent row.

90 Each of the segments is connected to the neutralizing coil of the call-registering relay corresponding thereto. For example, segment 3CU is connected to the neutralizing coil 13N of relay 13.

95 The selector FS further comprises a brush-carriage 4, shown in broken lines in Fig. 6, which carriage is moved in accordance with the movement of the car by any suitable mechanism and which has secured thereto a contact member 5 for successively engaging the aligned segments 1CU, 2CU, 3CU and 4CU as well as a contact member 7 secured thereto in spaced relation to contact member 5 for successively engaging the aligned segments BCD, 1CD, 2CD and 3CD.

100 The contact members 5 and 7 are connected to one of the supply conductors, namely L2, and the neutralizing coils are connected to the other supply conductor L1. Thus when the elevator 105

car is ascending and contact member 5 engages a "CU" segment, a circuit is completed for energizing the neutralizing coil which thus exerts a force counter to that exerted by the main coil of the relay and causes the relay to be actuated to a deenergized position. The opening of the contact members *a* of the call-registering relay opens the holding circuit for the main coil of the relay and the circuit for the neutralizing coil and thus effects the deenergization of both coils of the relay. The call previously registered on the relay, is thus cancelled.

A pair of relays 81 and 82 are provided which are normally energized as long as there are no calls registered. Whenever a call is registered by the operation of one of the push-button switches such as 4D, 3D, etc., one of the relays 81 or 82 is selectively deenergized to partially complete a circuit for energizing "up" direction relay 1 or "down" direction relay 2, respectively.

In order to effect the selective deenergization of relays 81 and 82, one terminal of each thereof is connected to a common supply conductor, namely L1, and the opposite terminals thereof are connected to each other through a series of normally closed contact members on all the call-registering relays, that is, the normally closed contact members *c* and *d* of relays 2B, 11, 12, 13, 14, 21, 22 and 23.

The common terminal of the contact members *c* and *d* of each call-registering relay is connected to a separate segment on the floor selector FS and the circuit for energizing relays 81 and 82 is completed therethrough to supply conductor L2 by means of contact members 8 and 9 secured to the brush-carriage 4 on the selector FS and electrically connected to the supply conductor L2 by flexible conductors or other suitable connecting means.

The segments on the floor selector include a plurality of "up" segments disposed in alinement in one series, the segments being designated 1FU, 2FU, 3FU and 4FU, corresponding, respectively, to floors #1, #2, #3 and #4.

The segments on the floor selector also include a plurality of "down" segments disposed in an adjacent alined series and designated BFD, 1FD, 2FD and 3FD corresponding, respectively, to the basement floor and floors #1, #2, and #3.

The common terminal of the contact members *c* and *d* of a relay for registering an "up" call is connected to an "up" or "FU" segment corresponding to the same floor as that to which the relay corresponds. For example, segment 3FU is connected to the common terminal of contact members *c* and *d* of relay 13.

Similarly, each "FD" segment is connected to the common terminal of the contact members *c* and *d* of the relay for registering a "down" call at the floor represented by the segment.

The contact member 8 on the brush carriage of the floor selector successively engages the segments 1FU, 2FU, 3FU, and 4FU, in accordance with the movement of the elevator car to floors #1, #2, #3 and #4, respectively. That is, the "FU" segments are of such length and are so disposed on the selector that contact member 8 engages a segment a predetermined time before the elevator car comes within the "up" slow-down zone of the floor to which the segment corresponds and continues to engage the segment until the elevator car ascends from that floor, at which time the contact member disengages the former segment, passes over an insulating segment and then engages the next

"FU" segment in the ascending direction. This is clearly shown in Fig. 6.

The "up" slow-down zone for a particular floor is, of course, the zone between the high-speed "up" inductor plate and the stopping inductor plate for the same floor. For example, the "up" slow-down zone for floor 1 is the zone between the inductor plate 1HU and the inductor plate 1SU.

The contact member 9 on the brush carriage of the floor selector is adapted to successively engage the "down" or "FD" segments in accordance with the approach of the elevator car to the floors to which the segments correspond.

The disposition of the "FD" segments on the floor selector and the lengths thereof is such that contact member 9 engages an "FD" segment before the elevator car comes within the "down" slow-down zone of the floor to which the segment corresponds and continues to engage the segment until the elevator car descends from that floor, at which time the contact member disengages the former segment, passes over an intervening insulating segment and then engages a succeeding "FD" segment 100 for the next floor in the direction of travel.

At the time the elevator car is at a floor both the contact members 8 and 9 are, respectively, in engagement with the "FU" and "FD" segments corresponding to that floor.

The insulating segments separating succeeding "FU" and "FD" segments are of such length as to cause the contact members 8 and 9, respectively, to completely disengage one segment before engaging the succeeding one. The purpose of such construction is to effect a momentary deenergization of either relay 81 or 82 as will be explained in greater detail hereinafter.

It will thus be seen that depending upon the relative positions of the contact members 8 and 9, corresponding to the positions of the elevator car in the hatchway, and that of the contact members *c* and *d* of the call-registration relay corresponding to the floor for which a call is registered, the circuit for energizing either of the relays 81 or 82 is selectively interrupted by the opening of the contact members *c* and *d* and the proper direction of movement of the elevator car, in response to the call registered thereby, subsequently effected.

Additional relays 38 and 80, actuatable in response to the deenergization of one of the relays 81 or 82, are employed for effecting the energization of relay 42, whereby a circuit for energizing the "up" direction relay 1 and the relay 6 or the "down" direction relay 2 and the relay 6 is completed to effect the starting of the elevator car in the proper direction in response to the call registered.

As a part of my invention, I provide a novel "biasing" control means which is independent of the push-button switches at the floors or on the car and which includes a plurality of relays or switches, for automatically effecting the movement of the elevator car to any one of a plurality of predetermined positions, after all registered calls have been completely responded to.

Included in the above-mentioned plurality of relays, is a relay 88 and a relay 87, which are selectively controlled by means of a double-throw switch 10. More specifically, if the double-throw switch is thrown to one position, relay 88 is rendered effective to cause the elevator car to move in one direction, such as the

downward direction, after all registered calls have been responded to. When the double-throw switch is thrown to the other position, relay 87 is rendered effective to cause the elevator car to move in the opposite or ascending direction.

A relay 70, of any suitable type for delaying the movement of the contact members thereof to their positions for a predetermined length of time after the relay is deenergized, is employed for preventing either of the relays 87 or 88 from becoming effective to influence the car into movement in the respective directions corresponding thereto, until a predetermined time,

such as ten seconds, elapses after the stopping of the car in response to the last registered call. Thus a passenger has ample time to open the car gate and hatchway door before the car starts to move under the automatic control of relays 87 or 88. Once the car gate or any hatchway door is opened, the interlock switches *g* and *ds* respectively opened thereby, prevent movement of the car. The interlock switches *g* and *ds* are reclosed, upon reclosure of the car gate and hatchway door, and permit the relays 87 or 88 to be energized and subsequently effect the automatic movement of the car.

Either one of a pair of relays 83 and 84 is selectively energized through normally open contact members of relays 1 and 2, respectively, and the normally open contact members of the call-registration relay which have been closed in response to the actuation of the corresponding push-button switch, when the contact members 8 or 9, depending upon whether the car is moving "up" or "down", respectively, engages the "FU" or "FD" segment corresponding to the floor for which a call has been registered. The opening of normally closed contact members on relays 83 or 84, caused by the energization thereof, interrupts the circuit for energizing either relay 87 or 88 to prevent the latter being effective to cause the elevator car to proceed to the predetermined floor corresponding thereto.

A relay 89 is employed having normally open contact members *b* thereof which are connected in parallel with normally closed contact members *a* of relay 70 and which close to establish a holding circuit for maintaining energized either of the relays 87 or 88 and 80 and 89 itself, at certain times when the normally closed contact members *a* of relay 70 are open.

The floor selector FS is additionally provided with three segments TTP, 1TP and BTP disposed in relative positions corresponding, respectively, to the positions of the elevator car at the top terminal floor, floor #1 and the basement floor (see Fig. 6). Segments TTP and 1TP are disposed in alinement and a contact member 14a on the brush-carriage 4 of the floor selector FS is adapted to engage either of the segments in accordance with the position of the elevator car and connect them to the supply conductor L2.

A contact member 15 is provided on the brush-carriage of the floor selector for engaging the segment BTP and connecting it to supply conductor L2.

The length of the segment TTP is such that the contact member 14a engages it when the elevator car approaches the top terminal floor, which in the present embodiment is the fourth floor, and before the elevator car enters the "up" slow-down zone for that floor. Assuming

that the double-throw switch 10 is thrown into the position for rendering the relay 87 effective to move the car upwardly after all calls are responded to, the engagement of contact member 14a with segment TTP completes a short-circuit connection around the coil of relay 87, thereby effecting its deenergization. When relay 87 is deenergized a circuit is completed for energizing the high-speed inductor relay H and thus when the inductor relay H passes the high-speed inductor plate 4HU, the deceleration and subsequent stopping of the elevator car at floor #4 is effected.

The length of the segment 1TP is such as to cause the contact member 14a to engage it during the descent of the car toward floor #1 before the car enters the "down" slow-down zone for floor #1 and such that the contact member 14a engages it during the ascent of the car to floor #1 before the car enters the "up" slow-down zone for floor #1. Thus, whether the elevator car is descending or ascending toward floor #1, the engagement of contact member 14a with the segment 1TP completes a short-circuit connection around the coil of relay 88, thereby effecting the deenergization thereof. The deenergization of relay 88 effects the energization of high-speed inductor relay H and the car is subsequently decelerated and stopped at floor #1.

The engagement of contact member 15 with segment BTP completes a circuit for energizing relay 87. By employing normally closed contact members *f* of relay 87 in the circuit for energizing relay 88, relay 88 is deenergized when the car is at the basement floor, while relay 87 is energized to cause the elevator car to automatically ascend. The length of the segment BTP is such that the contact member 15 disengages it a short interval of time after the contact member 14a engages the segment 1TP. Thus, once the elevator car begins to ascend towards floor #1 and contact member 15 disengages the segment BTP, both relays 87 and 88 are deenergized and the circuit for energizing the high-speed inductor relay H completed thereby to effect the subsequent deceleration and stopping of the elevator car at floor #1.

While I have illustrated an embodiment of my invention in which the elevator is biased either to the upper terminal floor or the first floor, after a predetermined time from the complete response to the last call registered, it should be understood that any other floors may be selected for the same purpose and the stopping thereof effected by additional segments and contact members corresponding to segments TTP and 1TP and contact members 14a and 15.

A knife-switch 16 is provided in the energizing circuit for relays 87 and 88 for opening the circuit permanently and thus preventing the automatic movement of the elevator car to a predetermined position after the complete response to the last call registered. In other words, by opening the knife-switch 16, the elevator car is caused to remain at the floor corresponding to the last call registered.

In order to simplify the control diagram, details of a floor control or door-operating system are omitted. In the subsequent description of my invention, the elevator car gate and the hatchway doors for the various floors will be described as manually operated because no mechanism for effecting the automatic operation of the doors is shown. However, it should be

understood that by employing the call-registering relays, such as 14, 13, 23, etc., to control a door-motor, the opening and closing of the doors may be readily effected automatically.

5 Furthermore, it should be understood that any other mechanism or method for automatically controlling the operation of the car-gate and hatchway doors may be readily employed in conjunction with my invention.

10 As previously mentioned, the control system, embodying my invention and shown in Figs. 1, 2 and 3, is illustrated as adapted to a building having a basement floor and four other floors designated #1, #2, #3 and #4.

15 Let it be assumed that the elevator car is stopped at floor #1, that the car-gate and hatchway door at the floor are closed, and that a call is registered at floor #4 by a passenger operating the push-button switch 4D.

20 The operation of the switch 4D closes a circuit for energizing the main coil 14M of relay 14 whereby the relay 14 is actuated to close its normally opened contact members *a* and *b* and to open its normally closed contact members *c* and *d*, which circuit extends from supply conductor L1 (Fig. 2) through conductor 17, push-button switch 4D, conductors 18 and 19, coil 14M and conductor 20 to supply conductor L2.

25 The closing of contact members *a* of relay 14 establishes a holding circuit for the coil 14M, because the contact members *a* are connected in parallel with the push-button switch 4D. Thus, although the push-button switch 4D, is released, relay 14 is maintained in an actuated condition to effect the registration of the call.

30 The closing of contact members *b* of relay 14 (see Fig. 3) prepares a circuit for energizing, selectively the relays 83 and 84 in the manner to be hereinafter described.

35 Relays 81 and 82 are both energized at the time that the elevator car is stopped and no other calls exist. The circuit for energizing relay 81 extends from supply conductor L1 (see Fig. 2) through conductor 25 to the point 26 and thence in two parallel branches to supply conductor L2. One of the branches from point 26 extends therefrom through the coil of relay 81, conductor 26a, through contact members *c* and *d* of relay 14, contact members *c* and *d* of relay 13, contact members *c* and *d* of relay 23, contact members *c* and *d* of relay 12, contact members *c* and *d* of relay 22 and contact members *c* of relay 11, all in series, to the point 27, thence through two parallel branches one of which extends through conductors 28 and 29, segment 1FU on the floor selector FS, contact member 8 on the brush carriage 4, conductor 30 through normally closed contact members *i* of relay 2, (see Fig. 2) and conductors 32 and 33 to supply conductor L2, and the other of which extends through conductor 34, contact members *d* of relay 11 in series with contact members *c* of relay 21, through conductors 35 and 36 to segment 1FD on the floor selector FS, through contact member 9 on the brush-carriage 4, through conductor 37, normally closed contact members *i* of relay 1 and conductors 32 and 33 to supply conductor L2.

40 The other branch of the parallel circuit extending from point 26 extends through the coil of relay 82, through conductor 40, contact members *d* and *c* of relay 2B and contact members *d* of relay 21, in series, to the point 41, thence through two parallel branches, the one extending

45 contact members *d* of relay 11 to the point 27 thence to supply conductor L2 as previously traced and the other branch extending through conductors 35 and 36 to the segment 1FD on the floor selector and thence to the supply conductor L2, as previously traced.

50 It will thus be understood that the circuit for energizing relay 81 is opened when contact members *c* and *d* of relay 14 are opened by the actuation thereof in response to the call registered at the fourth floor as assumed.

55 The deenergization of relay 81 effects the closing of contact members *b* thereof and they in turn complete a circuit for energizing relay 38, which extends from supply conductor L1, (see Fig. 2) through conductor 43, the coil of relay 38, conductor 44, contact members *b* of relay 81 and conductor 45 to supply conductor L2.

60 The energization of relay 38 completes a circuit for energizing relay 80, which circuit extends from supply conductor L1 (see Fig. 2) through conductor 46, normally closed contact members *a* of relay 70 (deenergized at this time), conductor 47, in series through normally closed contact members *b* of relay 83 and contact members *b* of relay 84, (both deenergized at this time) through conductor 48, coil of relay 80, conductor 49, contact members *b* of relay 38, (now closed), conductor 50 to the point 51 on Fig. 1 and thence by conductor 52 to supply conductor L2.

65 The energization of relay 80 effects the closing of contact members *a* thereof to prepare a circuit for energizing the relays 1 and 6, and also effects the closing of contact members *e* thereof to effect the energization of relay 42 when the door and gate interlock switches *d* and *g* are closed.

70 Contact members *f* of relay 80, when closed by the energization of that relay complete a circuit for energizing relay 89 which circuit extends from supply conductor L1 (Fig. 2) through conductor 46, contact members *a* of relay 70, conductor 47, contact members *b* of relay 83 and contact members *b* of relay 84 in series, conductors 48 and 48a, coil of relay 89, conductors 90 and 91, contact members *f* of relay 80 and conductors 92 and 93 to supply conductor L2.

75 Contact members *b* of relay 89, when closed by energization of that relay, complete a holding circuit which shunts the normally closed contact members *a* of relay 70 and thereby maintains the relays 80 and 89 energized.

80 Let it be assumed that the door and gate interlock switches *d* and *g* have closed, indicating that the elevator car is in a safe condition for starting. The closing of the switches *d* and *g* completes a circuit for energizing the relay 42, which extends from supply conductor L1 (see Fig. 1) through all of the door interlock switches *d* in series, through the gate interlock switch *g*, through conductor 53, contact members *e* of relay 80, conductors 54, 55, 56, coil of relay 42 and conductor 57 to supply conductor L2.

85 Relay 42, when energized, completes a circuit for energizing relays 1 and 6, which circuit extends from supply conductor L1 (Fig. 1) through the safety circuit including the previously described safety switches, through the stop switch suitably identified, coil of relay 6, conductor 58, coil of relay 1, conductor 59, contact members US on the stopping inductor relay S, conductor 60, contact members *d* of relay 2, conductor 61, contact members *a* of relay 81, conductor 62, contact members *a* of relay 83, conductor 63,

contact members *a* (now closed) of relay 80, conductor 64, contact members of relay 42 and conductor 65 to supply conductor L2.

The contact members *d* of relay 1, when closed by the energization of the relay, complete a shunting circuit around contact members *a* of relay 81, contact members *a* of relay 83 and contact members *a* of relay 80, and thereby establish a holding circuit for maintaining the relay 1 and 6 energized.

Contact members *b* and *c* of relay 1 when closed by the energization of relay 1 complete a circuit for energizing the generator field winding GF which circuit extends from supply conductor 15 L1 (Fig. 1) through conductor 66, contact members *b* of relay 1, conductor 67, generator field winding GF, conductor 68, contact members *c* of relay 1, conductor 69, resistors R1 and R2 in series, and conductor 71 to supply conductor L2.

20 Simultaneously with the energization of the generator field winding GF, the contact members *a* of relay 1 and the contact members of relay 6 complete a circuit for energizing relay 39 and the coil BC of the motor brake B, which circuit extends from supply conductor L1, through conductor 66, contact members *b* of relay 1, conductors 67 and 72, contact members *a* of relay 1, conductor 73, contact members of relay 6, thence through two parallel branches comprising, respectively, the coil of relay 39 and the brake coil BC, to the point 74, thence through conductor 75 to supply conductor L2.

Assuming, of course, that the motor DM is driving the armature GA of the generator G, the energization of the generator field winding GF causes the generator G to build up a voltage across its brush terminals which results in a flow of current in the loop-circuit comprising the winding of the armature MA of the elevator driving motor M. The brake coil BC, being energized simultaneously with the energization of the field winding GF, releases the brake shoe BS from engagement with the brake drum BD. The armature MA of the motor M thus starts to rotate at slow speed, incidently effecting the rotation of the hoist drum D to wind up the cable Ca thereon in such manner that the elevator car C ascends in the hatchway at slow speed.

50 Contact members *c* of relay 39, when closed by the energization of that relay, complete a shunting circuit around contact members *e* of relay 80, which circuit is clearly shown in Fig. 1, and thus establish a holding circuit for maintaining the coil of relay 42, energized, independently of whether or not the contact members *e* of relay 80 remain closed.

55 Contact members *a* of relay 39, when closed by the energization of that relay, complete a circuit for energizing relay 70 as well as partially completing a circuit for energizing the coil 3L of the high-speed inductor relay H, the latter circuit of which will be traced in detail hereinafter. The circuit for energizing relay 70, which is completed by the closing of contact members *a* of relay 39, extends from supply conductor L1 (Fig. 1) through conductor 76, contact members *a* of relay 39, conductor 77, coil of relay 70 and conductor 52 to supply conductor L2.

70 The closing of contact members *f* of relay 1, effected by the energization of that relay, completes a circuit for energizing relay GR5 which circuit extends from supply conductor L1 (Fig. 1), through conductor 78, contact members *f* of relay 1, conductor 79, contact members UI

of intermediate-speed inductor relay I, conductor 85, coil of relay GR5 and conductor 86 to supply conductor L2.

The closing of contact members *a* of relay GR5 completes a shunting circuit around the resistor R1 in the circuit for energizing the generator field winding GF, which results in an increased flow of current through the field winding GF, a further building-up of the voltage by the generator G, and an increased speed of rotation of the motor M which, of course, effects an increase in the speed of movement of the elevator car to a speed hereinafter designated as the "intermediate" speed.

80 By this time, the voltage across the brush terminals of the motor M is sufficient to energize the coil of voltage-responsive relay 31 and cause it to close its contact members.

85 The contact members of relay 31, when closed, complete a circuit for energizing the relay GR6, which circuit extends from supply conductor L1 (Fig. 1) through conductors 94 and 95, contact members *g* of relay 1, conductor 96, contact members UH of high-speed inductor relay H, conductor 97 to the point 98, thence through two parallel branches, the one comprising contact members *a* of relay 89, and the other comprising conductors 99, 100 and 101, contact members *c* of relay 80 and conductors 102 and 103, to the point 104, thence through conductor 105, contact members of relay 31, conductor 106, coil of relay GR6 and conductor 107 to supply conductor L2.

90 Contact members *b* of relay GR6, when closed by the energization of that relay, complete a third branch circuit in parallel with the two branch circuits comprising contact members *a* of relay 89 and contact members *c* of relay 80 in parallel, and thereby establish a self-holding circuit for the coil of relay GR6.

95 Contact members *a* of relay GR6, when closed by the energization of that relay, complete a shunting circuit around the resistor R2 and thereby effect an increased energization of the generator field winding GF, which results ultimately in the elevator car C accelerating to its highest speed of movement hereinafter designated as "high-speed".

100 Assuming that no other calls are registered between the elevator car and the call registered by the operation of the push-button switch 4D when the elevator car is ascending to the fourth floor in response to the call registered, the elevator car continues to move at high-speed until the contact member 8 on the brush carriage 4 of the floor selector FS, engages the segment 4FU thereof, whereupon a circuit is thereby completed for energizing relay 83 which circuit extends from supply conductor L1 (Fig. 2), through conductor 107, coil of relay 83, conductors 108 and 109, contact members *h* of relay 1, conductors 110, 111 and 112, contact members *b* of relay 14, conductor 113, floor selector segment 4FU, contact member 8, conductor 30, contact members *i* of relay 2 and conductors 32 and 33 to supply conductor L2.

105 The contact members *c* of relay 83, when closed by the energization of that relay, complete a holding circuit for the coil of relay 83, which circuit extends from supply conductor L1 (Fig. 2) through conductor 107, coil of relay 83, conductor 108, contact members *c* of relay 83, conductor 114, contact members *b* of relay 70, and conductors 115 and 116 to supply conductor L2.

When relay 83 is energized, the normally closed contact members *b* thereof open to interrupt the circuit, previously traced, for energizing relays 80 and 89.

- 5 When relay 80 is deenergized, the normally closed contact members *b* thereof are reclosed to complete a circuit for energizing the coil 3L of high-speed inductor relay H which circuit extends from supply conductor L1 (Fig. 1) 80 through conductor 76, contact members *a* of relay 39, conductor 117, contact members *b* of relay 87, contact members *b* of relay 88, contact members *d* of relay 80, conductors 118, 119 and 120, coil 3L of inductor relay H, and conductors 121 and 122 to supply conductor L2.

The elevator car, not having reached the high-speed inductor plate 4HU, the energization of the coil 3L of relay H is without immediate effect. However, when relay H on the car reaches the inductor plate 4HU, contact members UH of relay H open, in the manner previously described, to interrupt the circuit, previously traced, for energizing relay GR6.

The opening of contact members *a* of relay 25 GR6, caused by the deenergization of the relay, removes the short-circuit connection around resistor R2 in the circuit of the generator field winding GF and the current through the field winding GF is thus reduced due to the increased 30 resistance in circuit therewith. The reduction in the degree of energization of the field winding GF effects a deceleration in the speed of the elevator car so that the car moves at "intermediate" speed.

35 The closing of normally closed contact members *c* of the relay GR6 caused by the deenergization of the relay, completes a circuit for energizing the coil 2L of intermediate speed inductor relay I, which circuit extends from supply conductor L1, through conductor 76, contact members *a* of relay 39, conductor 117, contact members *b* of relay 87, contact members *b* of relay 88, contact members *d* of relay 80, conductors 118, 119 and 120, contact members *c* of relay GR6, conductor 123, coil 2L of inductor relay I and conductors 124, 121 and 122 to supply conductor L2.

The energization of coil 2L of relay I is of no effect until the relay I on the car passes the 50 intermediate speed inductor plate 4TU, at which time contact members UI of relay I open to interrupt the circuit, previously traced, for energizing relay GR5.

The opening of contact members *a* of relay 55 GR5, caused by the deenergization of the relay, opens the short-circuit connection around resistor R1 in the circuit of the field winding GF and thus causes additional resistance to be inserted in the field winding circuit to reduce 60 the speed of the elevator car to "slow speed".

The closing of normally-closed contact members *b* of relay GR5, caused by the deenergization of the relay, completes a circuit for energizing the coil 1L of stopping inductor relay S which circuit extends from supply conductor L1 through contact members *d* of relay 80, as 65 previously traced, conductor 118, contact members *b* of relay GR5, conductor 125, coil 1L of relay S and conductors 121 and 122 to supply conductor L2.

The energization of the coil 1L of relay S is of no effect until the inductor relay S on the car reaches the stopping inductor plate 4SU, at which time contact members US of relay S open, in the manner previously described, to

interrupt a circuit, previously traced, for energizing relays 1 and 6.

The deenergization of relays 1 and 6, as just described, effects the opening of the circuits, previously traced, for energizing the generator field winding GF, the brake coil BC and the coil of relay 39. As a result, therefore, the elevator car stops completely, the brake shoe BS is set on the brake drum BD by the biasing means provided, and the circuit, previously traced, for energizing the coils 3L, 2L and 1L of the inductor relays H, I and S, respectively, interrupted.

The voltage responsive relay 31 is, of course, deenergized when the voltage across the terminals of the winding of the motor armature MA falls to zero and the contact members thereof are thus caused to open, but such opening is of no effect because the relay GR6 controlled thereby has been previously deenergized, as just described.

The opening of contact members *a* of relay 39 and the opening of contact members *c* of relay 39 interrupts the circuits for energizing relays 70 and 42, respectively. As a result, these latter relays are, therefore, deenergized.

The reclosing of the normally closed contact members *b* of relay 70 is delayed a predetermined length of time, after the deenergization of the relay such as 10 to 20 seconds, by some suitable time-delay means, such as the dash pot 105 126, for the purpose of allowing some time in which the car-gate and hatchway door may be opened before permitting the relay 88 to be effective to automatically cause the elevator car to descend to the first floor in the manner 110 which will be hereinafter described.

When the elevator car attains the level of the floor to which it has moved in response to a call registered thereat, the contact member 5 on the brush-carriage 4 of the floor selector FS 115 engages the cancellation segment 4CU and a circuit is thereby completed for energizing the neutralizing coil 14N of relay 14 to effect the movement of the relay to its deenergized position and thus effect a cancellation of the call 120 previously registered by the operation of the push button switch 4D. The circuit for energizing coil 14N extends from supply conductor L1 (Fig. 2) through conductor 17, contact members *a* of relay 14, conductors 18 and 127, coil 14N, conductor 128, segment 4CU, brush or contact member 5 (see Fig. 3), conductor 129, contact members *c* of relay GR5 (Fig. 1) and conductor 130 to supply conductor L2.

The energization of coil 14N effects the opening of contact members *a* of relay 14 by overcoming the force holding those contact members closed which is exerted by the energized actuating coil 14M. The holding circuit for maintaining coil 14M energized, previously traced, is thus interrupted and relay 14 deenergized to cancel the call registered thereby.

The deenergization of relay 14 recloses the normally closed contact members *c* and *d* thereof and a circuit is thereby completed for re- 140 energizing relay 81 which circuit extends from supply conductor L1 (Fig. 2) through conductor 25, coil of relay 81, conductor 26a, contact members *c* of relay 14, (Fig. 3) conductor 131 to the point 132 and thence through conductor 113, 145 contact segment 4FU on the floor selector FS, contact member 8 on the brush-carriage 4, conductor 30, contact members *i* of relay 2, and conductors 32 and 33 to supply conductor L2.

The opening of the contact members *b* of relay 150

81, as a result of the energization thereof, effects the deenergization of relay 38 by interrupting the circuit, previously traced, for energizing the coil thereof.

5 It will thus be seen that the elevator car is stopped at the level of the upper terminal floor, namely floor #4, and that a passenger at floor #4 may open the hatchway door and car-gate to enter the car.

10 Let it be assumed, further, that the person registering the call does not open the hatchway door and the car-gate and that no other calls are registered.

15 After the expiration of the predetermined time previously mentioned, the contact members *b* of relay 70 open to interrupt the holding circuit, previously traced, for maintaining the relay 83 energized and thereby effect the deenergization thereof.

20 The deenergization of relay 83 causes the contact members *b* thereof to reclose and complete a circuit for energizing relay 88 which circuit extends from supply conductor L1 (Fig. 2) through conductor 46, contact members *a* of relay 70, conductor 47, contact members *b* of relay 83 and contact members *b* of relay 84, conductors 48, 133 and 134, contact members *d* of relay 82 and contact members *d* of relay 81, conductor 135, contact members *c* of relay 38, conductors 136 and 137, knife switch 16 (closed), conductor 138, resistor RB, conductors 139 and 140, normally closed contact members *f* of relay 87, coil of relay 88, conductor 141, contact arm 142 of double-throw switch 10 and conductor 143 to supply conductor L2.

25 The contact members *c* and *e* of relay 88, when closed by the energization of the relay, complete circuits for energizing, respectively, relays 42 and 89.

30 The circuit for energizing relay 42, established by contact members *c* of relay 88, is substantially that previously traced for contact members *e* of relay 80, the contact members *c* of relay 88 being connected in parallel with the contact members *e* of relay 80 as shown at the bottom of Fig. 1.

35 The circuit for energizing relay 89 is substantially that previously traced therefor, contact members *e* of relay 88 being connected in parallel with contact members *f* of relay 80 included in the circuit previously traced.

40 The contact members of relay 42 when closed, complete, at this time, a circuit for energizing relays 2 and 6, which circuit extends from supply conductor L1 (Fig. 1) through the safety circuit, stop switch, coil of relay 6, conductor 58, coil of relay 2, conductor 144, contact members DS of stopping inductor relay S, conductor 145, normally closed contact members *e* of relay 1, conductors 146 and 147, contact members *a* of relay 88, conductors 148, 149 and 64, contact members of relay 42, and conductor 65 to supply conductor L2.

45 A holding circuit for maintaining relays 2 and 6 energized independently of the contact members *a* of relay 88 is established by contact members *e* of relay 2 which are connected in parallel with contact members *a* of relay 88, as shown in the middle of Fig. 1.

50 It will be observed that the "down" direction relay 2 is thus selectively and automatically energized to effect a subsequent movement of the elevator car downwardly.

55 The brake coil BC and relay 39 are energized when contact members *a* of relay 2 and

the contact members of relay 6 close. Thus the brake B is released by coil BC to permit rotation of the motor armature MA and the circuit for energizing the inductor relay coils 3L, 2L and 1L is partially completed by the closing of contact members *a* of relay 39.

60 Contact members *f* of relay 2, when closed, complete a circuit for energizing relay GR5 which circuit extends from supply conductor L1 (Fig. 1) through conductor 150, contact members DI of inductor relay I, conductor 151, contact members *f* of relay 2, conductors 152 and 85, coil of relay GR5 and conductor 86 to supply conductor L2.

65 The closing of contact members *a* of relay 39 as a result of the energization thereof, completes a circuit for energizing relay 70 which circuit has been previously traced.

70 The elevator car is thus accelerated to intermediate speed when contact members *a* of relay GR5 complete a short-circuit connection around resistor R1 as previously described. The closing of contact members *a* of relay GR6, effected by means of voltage-responsive relay 31, completes a short circuit connection around resistor R2 to effect the acceleration of the elevator car to high-speed.

75 Assuming that no other calls are registered, the elevator car continues to descend at high-speed until the contact member 14a on the floor selector brush-carriage engages the segment 1TP.

80 The engagement of contact member 14a with segment 1TP closes a short circuit around the coil of relay 88 and the normally closed contact members *f* of relay 87 as clearly shown in Fig. 2 and thus effects the deenergization of relay 88.

85 The resistor RB is, thus, obviously employed to prevent a short-circuit across the supply conductors L1 and L2 by limiting the current through the circuit completed by the engagement of contact member 14a and segment 1TP.

90 When relay 88 is deenergized, the contact members *b* thereof close to complete a circuit for energizing the coil 3L of the inductor relay H which circuit has been previously traced.

95 The subsequent steps in the slow-down and stopping operation of the car having been previously described in detail and a repetition thereof is deemed unnecessary.

100 As a result of the slow-down and stopping operation, the car stops at floor #1 and stays there until a subsequent call is received. The car gate and hatchway door, of course, remain closed until opened manually by a passenger desiring to be transported from floor #1. It will be seen, therefore, that, thus far, a novel control system has been described for effecting, automatically, the movement of an elevator car to a predetermined position after the complete response to all registered calls, by means independent of the push-button switches at the floors or in the car and independent of the call-registration relay which are operable in response to the operation of the push-button switches.

105 In order to further describe the operation of the present control system embodying additional features of my invention, let it be assumed that when the elevator car was descending at high-speed from floor #4 and as it was passing floor #3, a call was registered at floor #4 by the operation of the push-button switch 4D.

In other types of elevator control systems hitherto known and employed, the elevator car would, under such circumstances, continue to travel to the predetermined position, under the influence of a biasing control, such as floor #1, and would not respond to the call at the fourth floor until it had arrived and stopped at floor #1.

In this respect, however, my invention effects a distinct advance in the art for the reason that I cause the elevator car, under the circumstances assumed, to slow down and stop at the next floor it approaches, the slow-down zone of which the car has not already entered, then reverse and respond immediately to the registered call without proceeding to the predetermined position such as floor #1. In other words, my invention effects a response of the elevator car to registered calls in preference to the automatic "biasing" control for returning the car to a predetermined position after all registered calls have been responded to.

Under the conditions assumed, therefore, the operation of push-button switch 4D completes a circuit for energizing the main coil 14M of relay 14, which circuit has been previously traced, and the contact members *a* of relay 14, when closed, complete a holding circuit for coil 14M as previously described.

Although contact members *c* and *d* of relay 14 open, relay 81 does not immediately become deenergized because a holding circuit is maintained therefore by contact members *f* of relay 88.

As the elevator car passes below floor #3, contact member 9 on the floor selector brush-carriage leaves the segment 3FD and engages the insulating member between segments 3FD and 2FD. A circuit for energizing the coil of relay 82 is thus interrupted, momentarily, and relay 82 becomes deenergized.

Contact members *b* of relay 82 are connected in parallel with contact members *b* of relay 81 and thus the reclosing of contact members *b* of relay 82, upon the deenergization thereof, completes a circuit for energizing relay 38 which has been substantially previously traced to include contact members *b* of relay 81. Contact members *b* of relay 38, when closed by the energization thereof, complete a circuit for energizing relay 80, which circuit has been previously traced.

As the elevator car continues to descend from floor #3, the contact member 9 on the floor selector brush-carriage engages the segment 2FD and thus recloses the circuit for energizing relay 82 which circuit extends from supply conductor L1 (Fig. 2) through conductor 25, coil of relay 82, conductor 40, contact members *d* and *c* of relay 2B, in series, (Fig. 3) contact members *d* and *c* of relay 21, in series, contact members *d* and *c* of relay 11 in series, contact members *d* of relay 22, conductors 155 and 156, segment 2FD, contact member 9, conductor 37, contact members *i* of relay 1 and conductors 32 and 33 to supply conductor L2 (Fig. 2).

The opening of contact members *b* of relay 82, upon the re-energization thereof, interrupts the circuit for energizing relay 38, and, as a result, the latter is de-energized.

The opening of contact members *b* of relay 38 as a result of the deenergization thereof, interrupts the circuit previously traced for energizing relay 80, and thus the latter is deenergized.

The opening of contact members *f* of relay 80, as a result of the deenergization of that relay, interrupts the holding circuit for relay 89, maintained thereby, and thus relay 89 becomes deenergized.

When relay 82 became re-energized by the completion of the circuit for energizing it as a result of the engagement of contact member 9 with the segment 2FD, it interrupted a holding circuit maintained for relay 88 by contact members *c* of relay 82, which circuit extends from supply conductor L1 (Fig. 2) through conductor 46, contact members *a* of relay 70, conductor 47, contact members *b* of relay 83 and contact members *b* of relay 84 in series, conductors 48, 133 and 157, contact members *d* of relay 88, conductor 158, contact members *c* of relay 82, conductors 159 and 137, knife-switch 16, conductor 138, resistor RB, conductors 139 and 140, contact members *f* of relay 87, coil of relay 88, conductor 141, contact arm 142 of double-throw switch 10 and conductor 143 to supply conductor L2.

Thus relay 88 becomes deenergized and the holding circuit for relay 81 maintained by the contact members *f* of relay 88 is interrupted and, as a result, relay 81 becomes deenergized because the open contact members *c* and *d* of relay 14 prevent the completion of a circuit for energizing relay 81 through the floor selector FS.

Contact members *b* of relay 81, when closed as a result of the deenergization of that relay, complete a circuit for energizing relay 38 which circuit has been previously traced.

During the interim between the deenergization and the re-energization of relay 38, relay 80 was de-energized as a result of the opening of contact members *b* of relay 38. Contact members *e* of relay 88, having previously opened as a result of the deenergization of relay 88, the opening of contact members *f* of relay 80 interrupted the holding circuit maintained thereby for energizing relay 89. Thus relay 89 became deenergized and because the contact members *a* of relay 70 and contact members *b* of relay 89 are simultaneously open, relay 80 cannot become re-energized when contact members *b* of relay 38 reclose.

When contact members *d* of relay 80 reclose as a result of the deenergization of relay 80, a circuit is completed thereby for energizing the coil 3L of the high-speed inductor relay H.

As the high-speed inductor relay H on the elevator car reaches the level of the "down" high-speed inductor plate 2HD, the contact members DH of relay H are opened and the car subsequently decelerated and stopped in the manner previously described by the successive operation of relays H, I and S.

It will thus be clear that although the elevator car was under the influence of relay 88 at the time it was automatically proceeding to floor #1 after responding to all prior registered calls, nevertheless, the registration of a call, behind the elevator car in its direction of movement, effected an immediate response thereto which resulted in the subsequent stopping of the car at the next floor, namely, in the example taken, floor #2.

Obviously, it is necessary that the elevator car be out of the "slow-down zone" of a floor when a call is registered in order that the car may stop at that floor. In other words, if the inductor relay H on the elevator car has already passed the high-speed inductor plate for a par-

ticular floor, the elevator car must proceed to the high-speed inductor plate corresponding to the next floor in order to stop.

The elevator car remains at the floor at which it stops, for a predetermined interval of time, such as 10 or 20 seconds, because of the time lag necessary for the contact members *a* of relay 70 to reclose and thereby complete a circuit for energizing relay 80.

10 Assuming then that the predetermined length of time required for the contact members *a* of relay 70 to reclose has expired, then relay 80 is energized thereby as previously described.

15 The closing of contact members *f* of relay 80, as a result of the energization thereof, completes a circuit for energizing relay 89, which circuit has been previously traced, and the closing of contact members *e* of relay 80 completes a circuit for energizing relay 42, which circuit has 20 also been previously traced.

25 The closing of the contact members of relay 42 completes a circuit for energizing relays 1 and 6, which circuit has been previously traced. It will be noted that the "up" direction relay 1 is energized.

30 Assuming no other calls to be registered, the elevator car starts to move upwardly, accelerates to high speed, decelerates and stops, in the manner previously described, at floor #4.

35 It remains at floor #4 a predetermined length of time as a result of the time lag on relay 70 in order to allow the hatchway door at the fourth floor and the car gate to be opened. The passenger, upon entering the elevator car, 40 closes the hatchway door and the car-gate and if he desires to go to floor #1 has the option of waiting until the car is automatically returned to floor #1, as previously described, or of operating the push-button switch 1C in the elevator car to effect movement thereof to floor #1.

45 The operation of push button switch 1C in the elevator car to cause the latter to move to floor #1 effects a sequence of operation which is substantially the same as previously described for the automatic movement of the car to the first floor but differs therefrom in some respects. The initial steps in the sequence of operations as a result of the operation of push button switch 1C will, therefore, be traced in detail.

50 The closing of the switch 1C completes a circuit for energizing the main coils 11M and 21M of relays 11 and 21 respectively, which circuit extends from supply conductor L1 (Fig. 3) through conductors 190, 191 and 192 to the common contact terminal 193 of push button switch 1C, thence through two parallel branches, the one extending through the contact member 194 of switch 1C, the terminal 195 of switch 1C, conductors 196 and 197, coil 11M and conductor 198 to the point 199, the other branch extending through the contact member 194 of the switch 1C, the contact terminal 200 of the switch 1C, conductors 201, 202 and 203, coil 21M and conductor 204 to the point 199, whence the circuit extends through conductor 205 to the supply conductor L2.

55 It will be remembered that at this time relay 88 is energized and that its contact members *f* are maintaining a holding circuit for the coil of relay 81, which circuit extends from supply conductor L1 (Fig. 2) through conductor 25, coil of relay 81, conductors 26a, 206, contact members *f* of relay 88 and conductors 207 and 208 to supply conductor L2. Thus the opening 70 of the contact members *c* and *d* of relay 11

and the opening of contact members *c* and *d* of relay 21, as a result of the energization of those relays, interrupts only the circuit for energizing relay 82, which circuit included contact members *c* and *d* of all of the relays 2B, 80 81, 11, 22, 12, 23 and 13, the contact members *d* of relay 14, conductors 131 and 113, segment 4FU and *b*, contact member 8 on the floor selector brush carriage which is connected to supply conductor L2 as previously described. 85

The closing of contact members *b* of relay 82, upon the deenergization thereof, completes the previously traced circuit for energizing relay 83, and as a result of the energization of relay 83, the contact members *b* of the latter relay 90 close to complete the previously traced circuit for energizing relay 89.

The closing of contact members *e* of relay 80 completes the previously traced circuit for energizing relay 42 and the closing of contact members *f* of relay 80 completes the previously traced 95 circuit for energizing relay 89.

Because relay 82 is de-energized, the contact members *a* thereof are closed and thus the closing of the contact members of relay 42 completes the circuit for energizing the "down" direction relay 2 and relay 6, which circuit has been described above.

The subsequent sequence of events in the acceleration of the elevator car downwardly to 105 high speed should be understood without a detailed description thereof.

When the elevator car, moving downwardly at high speed, attains a position in the hatchway such that the contact member 9 on the brush carriage of the floor selector engages the segment 1FD, a circuit is completed thereby for energizing relay 84, which circuit extends from supply conductor L1 (Fig. 2) through conductor 107, coil of relay 84, conductor 173, contact members *h* of relay 2, conductors 110, 111 and 209, contact members *b* of relay 21, conductor 36, segment 1FD on the floor selector, contact member 9 and thence to supply conductor L2, as 115 previously described. 120

The closing of contact members *c* of relay 84, as a result of the energization thereof, completes a holding circuit for maintaining relay 84 energized through the contact members *c* of relay 70 as previously described. 125

The opening of contact members *b* of relay 84, as a result of the energization thereof, interrupts the previously maintained circuit heretofore described for energizing relay 88 and as a result relay 88 becomes deenergized. 130

It will thus be seen that a "preference" is given to the established call instead of to the automatic biasing control effected by relay 88. The opening of contact members *b* of relay 84 also interrupts the previously traced circuit 135 for energizing relays 80 and 89 and they, therefore, become deenergized.

The closing of contact members *b* of relay 88 and the closing of contact members *d* of relay 80 thus complete the previously traced circuit 140 for energizing the coil 3L of the high speed inductor relay H.

The subsequent sequential operation of inductor relays H, I and S when the elevator car successively passes the inductor plates 1HD, 1ID and 1SD should be understood from previous descriptions thereof and it will, therefore, not be repeated. 145

When the elevator car stops at floor #1, contact members 5 and 7 on the floor selector brush 150

carriage engage segments 1CU and 1CD, respectively, and thereby complete, respectively, circuits for energizing the neutralizing coils 11N and 21N whereby the cancellation of the call registered thereon by the operation of the push button switch 1C is cancelled.

The reclosing of contact members *d* of relay 21, as a result of the deenergization thereof completes the circuit through the segment 1FD and contact member 9 of the floor selector for reenergizing relay 82. The opening of contact members *b* of relay 82 interrupts the previously described circuit for energizing relay 38 and the latter thus becomes deenergized.

When contact members *c* of relay 70 open after the predetermined time lag above-mentioned, the holding circuit, previously traced, for maintaining relay 84 energized is interrupted thereby and as a result, relay 84 becomes deenergized.

The elevator car is, therefore, stationed at floor #1 and the passenger who descended therein from floor #4 may open the car-gate and hatchway door at floor #1, leave the car and reclose the car-gate and hatchway door, after which the car waits indefinitely at floor #1 until a subsequent call is registered.

In order to still further explain the operation of the control system embodying my invention, let it be assumed that under the conditions above-described, that is, as the elevator car is being caused to move automatically to floor #1 from floor #4 under the influence of relay 88 and is just passing the level of floor #3, an "up" call is registered at floor #2 in advance of the car, by the operation of the push-button switch 2U.

The operation of switch 2U completes a circuit for energizing the main coil 12M of relay 12 which circuit extends from supply conductor L1 (Fig. 3) through conductor 160, contact members of switch 2U, conductors 161 and 162, coil 12M and conductor 163 to supply conductor L2.

The contact members *a* of relay 12 close, as a result of the energization of the relay, and being connected in parallel with the switch 2U, establish a holding circuit for maintaining coil 12M energized, although the push button switch 2U is released.

The opening of contact members *c* and *d* of relay 12 interrupts the circuit for energizing the relay 82 previously maintained by the engagement of contact member 9 with segment 3FD on the floor selector which circuit extends from supply conductor L1 (Fig. 2) through conductor 25, coil of relay 82, conductor 40, contact members *d* and *c* of relay 2B (Fig. 3), contact members *d* and *c* of relay 21, contact members *d* and *c* of relay 11, contact members *d* and *c* of relay 22, contact members *d* and *c* of relay 12, contact members *d* of relay 23, conductors 164 and 165, segment 3FD, contact member 9 on the brush-carriage 4, conductor 37, contact members *i* of relay 1 and conductor 32 and 33 to supply conductor L2.

The closing of contact members *b* of relay 82, upon the deenergization of the relay, completes a circuit for energizing relay 38, which circuit has been previously traced.

The opening of contact members *b* of relay 38, as a result of the deenergization of the relay, interrupts the circuit previously maintained thereby for energizing relay 80, which circuit is

clearly shown at the top of Fig. 2 and which has also been previously traced.

As has been previously mentioned, the insulating segment between the segment "3FD" and segment "2FD" is of such length as to effect a disengagement of contact member 9 from both of the segments during transition from one to the other.

If such construction were not employed, that is, if contact member 9 engaged the segment 2FD before it disengaged the segment 3FD, relay 82 would not be deenergized. As will be apparent from the subsequent sequence of operations it is necessary that relay 82 be de-energized in order to effect a deenergization of relay 88 and an immediate preferential response to the registered call.

As the elevator car continues to descend, the contact member 9 engages the segment 2FD before the inductor relay H comes within the "down" slow down zone for floor #2. Thus relay 82 is again energized by the completion of a circuit therefor through segment 2FD and contact member 9, which circuit is substantially the same as that previously traced and which includes the segment 3FD.

The energization of relay 82 effects the opening of contact members *b* thereof, and thus the circuit for energizing relay 38 is interrupted with the result that relay 38 becomes deenergized.

The opening of contact members *c* of relay 82 interrupts the holding circuit maintained thereby for energizing relay 88, which circuit has been previously traced, and thus relay 88 becomes deenergized.

As a result of the opening of contact members *f* of relay 88, the holding circuit for the coil of relay 81 maintained thereby is interrupted and since the contact members *c* and *d* of relay 12 are open at this time due to the registration of a call by the relay 12, the circuit for energizing relay 81 through the segment 2FD on the floor selector and contact member 9 is not complete. Thus relay 81 becomes deenergized by the opening of contact members *f* of relay 88.

The closing of contact members *b* of relay 81 due to the deenergization of the relay, completes the heretofore well identified circuit for energizing relay 38, and relay 38, as a result, becomes energized.

During the interim between the de-energization and the re-energization of relay 38, relay 80 was, of course, deenergized as previously described. As a result of the de-energization of the relay 80 the circuit for energizing relay 89 was interrupted by the opening of contact members *f* of relay 80 and, as a result, relay 89 became de-energized before relay 38 became re-energized.

As a result of de-energization of relay 89, relay 80 could not be re-energized upon the re-energization of relay 38 because the contact members *b* of relay 89 which are connected in parallel with contact members *a* of relay 70 and which serve to complete the holding circuit for relay 80, are open.

Thus, relay 80 remaining de-energized, the contact members *d* thereof complete a circuit for energizing the coil 3L of high-speed inductor relay H, which circuit has been previously well described.

As the elevator car continues to descend the inductor relay H thereon enters "down" slow-

down zone, that is, it passes the "down" high-speed inductor plate 2HD for floor #2.

As a result, contact members DH of relay H open to effect de-energization of relay GR6. 5 The subsequent sequence of operation until the elevator car is stopped completely at floor #2 need not be described here in detail because it is similar to that already described.

10 The passenger at floor #2 manually opens the hatchway door at the floor and the car gate, enters the car and recloses the door and gate behind him.

Assuming that the passenger who entered the elevator car at floor #2 desires to ascend to 15 floor #4, such movement of the elevator car to floor #4 without proceeding to floor #1, is effected by the operation of push button switch 4C in the elevator car. The sequence of operations effected by the operation of push button 20 switch 4C is believed to be sufficiently understood at this time so that a detailed description thereof is not required.

25 After the elevator car stops at floor #4, the passenger opens the car-gate and hatchway door, leaves the car and recloses the car-gate and hatchway door—after which the car is automatically returned to floor #1 in the manner previously described.

30 Let it now be assumed that a call is registered at the basement floor by the operation of the push-button switch BU thereof. The operation of the switch BU completes a circuit for energizing the main coil 2BM of relay 2B which circuit extends from supply conductor L1, (Fig. 3), 35 through conductors 166 and 167, switch BU, conductors 168 and 169, coil 2BM and conductor 170 to supply conductor L2. The normally open contact members *a* of relay 2B are connected in parallel with the switch BU and the closing thereof, as a result of the energization of relay 2B, completes a holding circuit for maintaining relay 2B energized.

45 The opening of contact members *c* and *d* of relay 2B interrupts the circuit by which relay 82 is energized, which circuit extends from supply conductor L1 (Fig. 2) through conductor 25, coil of relay 82, conductor 40, contact members *d* and *c* of relay 2B (Fig. 3), contact members *d* of relay 21 to the point 41, thence through two 50 parallel branches, one comprising the segment 1FD and contact member 9 of the floor selector connected to supply conductor L2 as previously described, and the other comprising contact members *c* of relay 21, contact members *d* of relay 11, segment 1FU and contact member 8, the latter being connected to the supply conductor L2 are previously described.

55 Therefore, when the contact members *c* and *d* of relay 2B are opened, as a result of the energization of relay 2B, the circuit for energizing relay 82 is interrupted and the latter becomes deenergized.

60 The reclosing of normally-closed contact members *b* of relay 82 completes the circuit, already described, for energizing relay 38, which thus becomes energized.

65 The closing of contact members *b* of relay 38, as a result of the energization thereof, completes the previously described circuit for energizing relay 80 and thus relay 80 becomes energized.

70 The closing of contact members *e* and *f* of relay 80 complete the individual circuits, previously traced, for energizing relays 42 and 89, 75 respectively.

80 The closing of the contact members of relay 42 completes a circuit for energizing the relays 2 and 6, which extends from supply conductor L1 (Fig. 1) through the safety circuit, stop switch, coil of relay 6, conductor 58, coil of relay 2, conductor 144, contact members DS of stopping inductor relay S, conductor 145, contact members *e* of relay 1, conductor 146, contact members *a* of relay 82, conductor 171, contact members *a* of relay 84, conductor 172, contact members *b* of relay 89, conductors 149 and 64, contact members of relay 42 and conductor 65 to supply conductor L2.

85 It will thus be seen that the "down" direction relay 2 is selectively energized to effect the descent of the elevator car.

90 It is deemed unnecessary to trace in detail the steps in the acceleration of the car because such operation has already been described. It is to be noted, however, that in a case where the car is required to move only the distance between two adjacent floors, the voltage-responsive relay 31 may not be actuated and the elevator car may not therefore, attain high speed. Let it be assumed, however, that the elevator car 95 may attain high speed in cases where it is required to move only the distance between adjacent floors.

100 As the elevator car descends, the contact member 9 on the brush-carriage of the floor selector engages the segment BFD and a circuit is thereby completed for energizing relay 84 which circuit extends from supply conductor L1 (Fig. 2) through conductor 107, coil or relay 84, conductor 173, contact members *h* of relay 2, conductors 110 and 111, contact members *b* of relay 2B, (Fig. 3) conductor 174, segment BFD, contact member 9, conductor 37, contact members *i* of relay 1, and conductors 32 and 33 to supply conductor L2.

110 The opening of contact members *b* of relay 84 interrupts the circuit for energizing both of the relays 80 and 89, which circuit has already been traced, and thus the latter two relays become deenergized.

115 The reclosing of contact members *d* of relay 80 completes a circuit for energizing the coil 3L of inductor relay H, which circuit has already been traced.

120 The subsequent deceleration and stopping of the elevator car by the inductor relays H, I and S as the car moves past inductor plates BHD, BID, and BSD, respectively, (Fig. 6) is thought to be well understood and a detailed description of their operation is omitted.

125 When the elevator car arrives substantially at the basement floor, contact member 7 on the brush-carriage of the floor selector engages the segment BCD and a circuit is thereby completed for energizing the neutralizing coil 2BN of relay 2B which circuit extends from supply conductor L1 (Fig. 3) through conductors 166 and 167, contact members *a* of relay 2B, conductors 168 and 169, coil 2EN, conductor 175, segment BCD, contact member 7, conductor 176, contact members *d* of relay GR5 (Fig. 1), and conductors 177 and 130 to supply conductor L2. The contact members *a* of relay 2B are thus caused to open, as will be understood from a 130 previous description of the operation of the call-registering relays, and the holding circuit maintained by contact members *a* is interrupted—whereby the main coil 2BM of relay 2B is deenergized. The call registered at the basement 135

floor by the operation of push button switch BU is thus cancelled.

The reclosing of contact members *d* of relay 2B as a result of the de-energization of relay 2B completes a circuit for re-energizing relay 82 which extends from supply conductor L1 (Fig. 2) through conductor 25, etc. to the point 178 common to the contact members *c* and *d* of relay 2B (Fig. 3) and thence through conductors 179 and 174, selector segment BFD, contact member 9, to supply conductor L2 as previously traced.

The opening of contact members *b* of relay 82, as a result of the energization of relay 82, 15 interrupts the circuit for energizing relay 38 previously maintained thereby and thus relay 38 becomes deenergized.

Let it be assumed, therefore, that the elevator car stops properly at the basement floor and, as a result of the time delay in the reclosing of contact members *b* of relay 70, waits a predetermined length of time for the passenger at the basement floor to open the hatchway door thereat and the car-gate.

25 Assuming that the car-gate and hatchway door at the basement floor are not opened, the opening of contact members *c* of relay 70 after the expiration of the predetermined time opens the holding circuit for maintaining the relay 30 84 energized, which circuit extends from supply conductor L1 (Fig. 2) through conductor 107, coil of relay 84, conductors 173 and 180, contact members *c* of relay 84, conductor 181, contact members *c* of relay 70 and conductor 116 35 to supply conductor L2.

Contact member 15 on the floor selector brush-carriage being now in engagement with the segment BTP, the deenergization of relay 84 and the reclosing of normally-closed contact members *b* thereof effects the completion of a circuit for energizing relay 87 which circuit extends from supply conductor L1 (Fig. 2) through conductor 46, contact members *a* of relay 70, conductor 47, contact members *b* of relay 83, 45 contact members *b* of relay 84, conductors 48, 133 and 134, contact members *d* of relay 82, contact members *d* of relay 81, conductor 135, contact members *c* of relay 38, conductors 136 and 137, knife switch 16, conductors 138 and 50 182, resistor RT, conductors 183 and 184, coil of relay 87, conductor 185, segment BTP, contact member 15 on the floor selector brush-carriage, and conductor 186 to supply conductor L2.

Resistor RT is provided for a purpose similar 55 to that of resistor RB and it limits the short-circuit current where relay 87 is shunted by the engagement of segment BTP and contact member 15.

60 The opening of contact members *f* of relay 87 interrupts the circuit for energizing relay 88 which would otherwise be energized because the contact member 14*a* is not in engagement with the segment 1TP at the time that the elevator 65 car is at the basement floor.

The closing of normally opened contact members *e* of relay 87 completes a circuit for energizing relay 89 which circuit extends from supply conductor L1 (Fig. 2) to the coil of relay 89 as previously traced, thence through conductor 90, contact members *e* of relay 87 and conductor 93 to supply conductor L2.

70 The closing of contact members *b* of relay 89 completes a holding circuit for maintaining 75 relay 89 energized independently of whether

or not the normally closed contact members *a* of relay 70 are closed or open.

The normally open contact members *c* of relay 87, when closed, complete a circuit for energizing relay 42 which circuit extends from supply conductor L1 (Fig. 1) through the door and gate interlock switches *ds* and *g* in series, conductors 53 and 187, contact members *c* of relay 87, conductors 55 and 56, coil of relay 42 and conductor 57 to supply conductor L2.

80 The contact members of relay 42, when closed by the energization of the relay, complete a circuit for selectively energizing relays 1 and 6, which circuit extends from supply conductor L1 (Fig. 1) through the safety circuit, stop switch, coil of relay 1, conductor 59, contact members US of stopping inductor relay S, conductor 60, normally closed contact members *d* of relay 2, conductors 61 and 188, contact members *a* of relay 87, conductors 189, 149, and 64, contact members of relay 42, and conductor 65 to supply conductor L2.

85 The contact members of relay 42, when closed by the energization of the relay, complete a circuit for selectively energizing relays 1 and 6, which circuit extends from supply conductor L1 (Fig. 1) through the safety circuit, stop switch, coil of relay 1, conductor 59, contact members US of stopping inductor relay S, conductor 60, normally closed contact members *d* of relay 2, conductors 61 and 188, contact members *a* of relay 87, conductors 189, 149, and 64, contact members of relay 42, and conductor 65 to supply conductor L2.

90 The contact members of relay 42, when closed by the energization of the relay, complete a circuit for selectively energizing relays 1 and 6, which circuit extends from supply conductor L1 (Fig. 1) through the safety circuit, stop switch, coil of relay 1, conductor 59, contact members US of stopping inductor relay S, conductor 60, normally closed contact members *d* of relay 2, conductors 61 and 188, contact members *a* of relay 87, conductors 189, 149, and 64, contact members of relay 42, and conductor 65 to supply conductor L2.

95 The contact members of relay 42, when closed by the energization of the relay, complete a circuit for selectively energizing relays 1 and 6, which circuit extends from supply conductor L1 (Fig. 1) through the safety circuit, stop switch, coil of relay 1, conductor 59, contact members US of stopping inductor relay S, conductor 60, normally closed contact members *d* of relay 2, conductors 61 and 188, contact members *a* of relay 87, conductors 189, 149, and 64, contact members of relay 42, and conductor 65 to supply conductor L2.

100 A holding circuit is established for maintaining the relay 1 energized independently of the contact members *a* of relay 87, by normally opened contact members *d* of relay 1 which are connected in parallel with the contact members *a* of relay 87.

105 It will thus be observed that the "up" direction relay has been energized to effect the movement of the elevator car upwardly.

The succeeding steps in the acceleration of the elevator car to intermediate speed or high speed will not be traced because they will be understood from previous description.

110 Let it be assumed therefore that the elevator car has accelerated to high-speed upwardly. When the contact member 15 disengages the segment BTP, the circuit for energizing relay 87, previously traced, is interrupted thereby and the de-energization of relay 89 and the energization of the relay 3L of the high speed inductor relay H effected, respectively, by the opening of contact members *e* of relay 87 and the closing of contact members *b* of relay 87.

115 The subsequent steps in the deceleration and stopping of the elevator car by the operation of the inductor relays H, I and S when the elevator car passes inductor plates 1HU, 1IU, and 1SU will be readily understood from previous description without a detailed explanation here. It will thus be apparent that the elevator car is properly and automatically stopped at floor #1, because the "up" slow-down and stopping inductor plates 1HU, 1IU and 1SU are the first inductor plates to be passed by the inductor relays after initial energization of coil 3L of relay 3H.

120 It will thus be seen that the elevator car automatically returns to floor #1 whether the call last registered and responded to is above or below floor #1.

125 Although the present embodiment of my invention is illustrated for a condition wherein a predetermined position or floor to which the car is automatically returned after the complete response to all registered calls is adjacent to the lowermost floor, that is adjacent to the basement floor, it should be understood that the segment BTP on the floor selector may be readily lengthened to maintain the continued energization of relay 87 whereby the car will move any predetermined distance instead of merely the distance between adjacent floors. Thus, floor #2 or floor #3 may be taken as

the predetermined position which, in the present embodiment, is illustrated as being floor #1.

Other hypothetical instances might be assumed and the sequence of operations incident thereto traced and described in detail, but it is thought to be unnecessary to further extend the length of this specification, for the reason that the foregoing description and assumed instances of operation are deemed to comprehensively explain and describe the structure and method of operation of the control system illustrating and embodying my invention.

It should be understood, moreover, that although the above assumed instances of operation describe merely one call as being registered at a time, it is possible to register a plurality of calls to which the elevator car will respond in succession. For example, if the elevator car is proceeding to the first floor as the predetermined position to which it returns after the complete response to the last call registered, and a plurality of calls are registered between the car and the first floor, the car will stop successively at the various floors at which calls have been registered.

In further explanation of the operation of the control system illustrating the present embodiment of my invention, it should be understood, also, that in the event a plurality of "up" calls and a plurality of "down" calls are registered substantially at the same time, the elevator car will proceed upwardly stopping only at the floors at which "up" calls have been registered and will continue upwardly to the most remote floor at which a call, be it "down" or "up", is registered, then reverse and descend, stopping only at the floors at which "down" calls have been registered. It is difficult to describe in detail a sequence of events for such a condition as the foregoing because of the small number of floors taken to illustrate the present embodiment of my invention. However, such a detailed description is deemed unnecessary because it will be apparent that the control system illustrated is capable of so functioning.

Although I have not described in detail the exact sequence of events when the double throw switch 10 is thrown into a position to render the relay 87 effective to cause the elevator car to move to the upper terminal floor as the predetermined position to which it will always return after the complete response of the elevator car to the last call registered, such sequence should be readily understood from the foregoing description of the sequence in connection with relay 88, and the operation of relay 87 in connection with the automatic return of the elevator car to floor #1 from the basement floor.

It will thus be understood that in the early morning when the tenants of an apartment house are leaving, the double throw switch 10 may be thrown to the position for rendering relay 87 effective to cause the elevator car to return automatically to the upper terminal floor, since the least amount of travel of the elevator car is thereby necessary, in most instances, to bring the car to the floor at which a call is registered. During the evening hours when the tenants of the apartment house are returning, the double throw switch may be thrown to the position rendering relay 88 effective to automatically return the car to floor #1 after the complete response to the last call registered, because by so doing, the car will be thereby, most

readily available with the least amount of delay to the tenants.

It will, therefore, be seen that I have disclosed a novel control system for an elevator car whereby it is influenced or biased to one predetermined position or optionally to any one of a plurality of predetermined positions automatically, after the car has completely responded to the last call registered.

It will also be seen that I have disclosed an elevator control system for operating an elevator car most efficiently and comprising means for giving a registered call preference over the biasing control elements embodied therein so that the elevator car moves to the floor at which a call is registered in the shortest time practicable.

It should be understood that the diagram of the control system accompanying this specification is intended to be illustrative of but one of many embodiments which are possible without departing from the spirit and scope of my invention. I desire, therefore, not to restrict the scope of my invention except as limited by the scope of the prior art and by the appended claims.

I claim as my invention:

1. In an elevator control system, motive means for moving an elevator car in a hatchway past a plurality of floors, reversing means for starting and stopping said motive means, call-registration means operable to control said reversing means to cause said motive means to move the car to any of the floors and stop it thereat, and means responsive to a condition in which none of said call registering means is operated, for controlling said reversing means to cause said motive means to move the car to a predetermined position and stop it thereat.

2. In an elevator control system, motive means for moving an elevator car in a hatchway past a plurality of floors, reversing means for starting and stopping said motive means, call-registration means including a relay for each floor operable to control said reversing means to cause said motive means to move the car to any of the floors and stop it thereat, and means responsive to a non-operated condition of all of said relays, for controlling said reversing means to cause motive means to move the car to any of a plurality of predetermined positions and stop it thereat.

3. In an elevator control system, motive means for moving an elevator car in a hatchway past a plurality of floors, reversing means for starting and stopping said motive means, call-registration means for controlling said reversing means to cause said motive means to move the car to any of said floors and stop it thereat, a plurality of additional means which are each effective when said call-registration means is not effective to cause movement of the car, for controlling said reversing means to cause it to move the car to predetermined positions corresponding to the said additional means respectively and stop it thereat, and means for causing only one of said additional means to be effective at one time.

4. In an elevator control system, motive means for moving an elevator car in a hatchway past a plurality of floors, reversing means for starting and stopping said motive means, call-registration means including a relay for each floor operable to control said reversing means to cause said motive means to move the car to any of said floors and stop it thereat, and

- additional means effective when said call-registration means is not effective to cause movement of the car, for controlling said reversing means to cause said motive means to move the car to a predetermined position and stop it thereat, said additional means including electro-responsive means operably responsive to the non-operated condition of all of said relays for actuating said reversing means to start said car, means 10 movable in accordance with the movement of the car for restoring said electro-responsive means to non-operated condition, and means operably responsive to the restoration of said electro-responsive means for controlling said reversing means to stop the car at the predetermined position.
5. In an elevator control system, motive means for moving an elevator car in a hatchway past a plurality of floors, reversing means for starting and stopping said motive means, call-registration means for controlling said reversing means to cause said motive means to move the car to any of the floors and stop it thereat, and additional means effective when said call-registration means is not effective to cause movement of the car, for controlling said reversing means to cause said motive means to move the car to a predetermined position and stop it thereat, said additional means including electro-responsive means actuatable to control said reversing means to cause it to effect movement of the car to the predetermined position, interlocking means operable when said call-registration means is not effective to cause movement of the car, for effecting the actuation of said electro-responsive means, means for effecting the de-actuation of said electro-responsive means, including a floor selector having a segment and a means movable in accordance with the movement of the car for engaging said segment to complete a shunting circuit around said electro-responsive means to effect its de-actuation, and means operably responsive to the de-actuation of said electro-responsive means for controlling said reversing means to stop the car at the predetermined position.
6. In an elevator control system, motive means for moving an elevator car in a hatchway past a plurality of floors, reversing means for starting and stopping said motive means, means including call-registration means, for controlling said reversing means to effect movement of the car to any of said floors and stop it thereat, and biasing control means for automatically causing the car to be moved to a predetermined position intermediate the uppermost and lowermost floors and stopped thereat when no calls are registered by said call-registration means, said biasing control means including an electro-responsive means actuatable when said call-registration means is not effective to control said reversing means, for controlling said reversing means to cause it to effect movement of the car in a predetermined direction toward said predetermined position, a second electro-responsive means actuatable when said call-registration means is not effective to control said reversing means, for controlling said reversing means to cause it to effect movement of the car in a direction opposite to said predetermined direction, means effective when the car is in a position on one side of said predetermined position for selectively energizing one of said electro-responsive means and effective when the car is in a position 75 on the other side of said predetermined position for selectively energizing the other of said electro-responsive means, and means including means movable in accordance with the movement of the car, for controlling said reversing means to cause it to effect the stopping of the said motive means when the car reaches the predetermined position.
7. In an elevator control system, motive means for moving an elevator car in a hatchway past a plurality of floors, reversing means for starting and stopping said motive means, an up-direction call-means and a down-direction call-means at each floor, a plurality of call-means disposed in the car and corresponding respectively to successive floors, call-registration means actuatable in response to the operation of said call-means, an electro-responsive means for controlling said reversing means to cause it to effect movement of said motive means in one direction, a second electro-responsive means for controlling said reversing means to cause it to effect movement of said motive means in a direction opposite to said one direction, means including said call-registration means and means movable in accordance with the movement of the car, for effecting the energization of both of said electro-responsive means when said call-registration means is not actuated, said electro-responsive means being selectively de-energized by the actuation of said call-registration means, whereby 105 said reversing means is selectively controlled to effect movement of said motive means in either one direction or the other in accordance with the electro-responsive means de-energized.
8. In an elevator control system, motive means for moving an elevator car in a hatchway past a plurality of floors, reversing means for starting and stopping said motive means, an up-direction call-means and a down-direction call-means at each floor, a plurality of call-means disposed in the car and corresponding respectively to successive floors, call-registration means actuatable in response to the operation of said call-means, an electro-responsive means for controlling said reversing means to cause it to effect movement of said motive means in one direction, a second electro-responsive means for controlling said reversing means to cause it to effect movement of said motive means in a direction opposite to said one direction, means which includes said call-registration means and means movable in accordance with the movement of the car, for effecting the energization of both of said electro-responsive means when said call-registration means is not actuated, said electro-responsive means being selectively de-energized by the actuation of said call-registration means, whereby said reversing means is selectively controlled to effect movement of said motive means in either one direction or the other 130 in accordance with the electro-responsive means deenergized, and means operably responsive to the condition of said call-registration means and the position of said means movable in accordance with the movement of the car, for controlling said reversing means to cause it to stop said car.
9. In an elevator control system, motive means for moving an elevator car in a hatchway past a plurality of floors, reversing means for starting and stopping said motive means, an up-direction call-means and a down-direction call-means at each floor, a plurality of call-means disposed in the car and corresponding respectively to successive floors, call-registration means actuatable 145

- in response to the operation of said call-means, an electro-responsive means for controlling said reversing means to cause it to effect movement of said motive means in one direction, a second 5 electro-responsive means for controlling said reversing means to cause it to effect movement of said motive means in a direction opposite to said one direction, means which includes said call-registration means and means movable in accordance 10 with the movement of the car, for effecting the energization of both of said electro-responsive means when said call-registration means is not actuated, said electro-responsive means being selectively deenergized by the actuation of said call-registration means, whereby 15 said reversing means is selectively controlled to effect movement of said motive means in either one direction or the other in accordance with the electro-responsive means de-energized, 20 means operably responsive to the condition of said call-registration means and the position of said means movable in accordance with the movement of the car, for controlling said reversing means to cause it to stop said car, means including means which is actuatable when said call-registration means is not actuated, for selectively controlling said reversing means independently of said call-registration means to cause said motive means to effect movement of the car to a 25 predetermined position and stop it thereat.
10. In an elevator control system, motive means for moving an elevator car in a hatchway past a plurality of floors, reversing means for starting and stopping said motive means, call-registration means operable to control said reversing means to cause it to effect movement of the car to any of the floors and stop it thereat, biasing control means effective when the said call-registration means is not effective to cause 30 movement of the car, for controlling said reversing means to cause said motive means to move the car to a predetermined position and stop it thereat, and means for rendering said biasing control means ineffective to control said reversing means when said call-registration means is operated during the time that the car is proceeding to the predetermined floor under the influence of said biasing control means.
11. In an elevator control system, motive means for moving an elevator car in a hatchway past a plurality of floors, reversing means for starting and stopping said motive means, call-registration means operable to control said reversing means to cause it to effect movement of the car to any of the floors and stop it thereat, additional means effective when the said call-registration means is not effective to cause movement of the car, for controlling said reversing means to cause said motive means to move the car to a predetermined position and stop it thereat, and means for rendering said additional means ineffective to control said reversing means when a call-registration means is operated during the time that the car is proceeding to the predetermined floor under the influence of said additional means.
12. In an elevator control system, motive means for moving an elevator car in a hatchway past a plurality of floors, reversing means for starting and stopping said motive means, call-registration means operable to control said reversing means to effect movement of the car to any of the floors and stop it thereat, biasing control means effective when the said call-registration means is not effective to cause movement 75 of the car, for controlling said reversing means to cause said motive means to move the car to a predetermined position and stop it thereat, and means for rendering said biasing control means ineffective to cause movement of the car to a predetermined position and stop it thereat, and means operably responsive to the operation of said call-registration means as the car is proceeding to the predetermined floor under the influence of the said biasing control means, for causing said reversing means to be controlled by said call-registration means in preference to said biasing control means regardless of the location 85 of the call with respect to the car.
13. In an elevator control system, motive means for moving an elevator car in a hatchway past a plurality of floors, reversing means for starting and stopping said motive means, call-means at the floors and in the car, means operably responsive to the operation of the call means, for registering a plurality of calls and controlling said reversing means to cause it to effect movement of the car to the floors corresponding to the calls registered, means movable in accordance with the movement of the car, deceleration means controlled by said call-registering means and said means movable in accordance with the movement of the car, operable to 95 control said reversing means to cause it to stop the car at the floors for which calls have been registered, biasing control means operable when no calls are registered, for controlling said reversing means to cause said reversing means to 100 effect movement of the car toward a predetermined position, means including said means movable in accordance with the movement of the car, for rendering said biasing control means ineffective as the car approaches the predetermined position and for rendering said deceleration means effective as the car approaches the predetermined position, whereby said car is stopped at the predetermined position, and means operably responsive to the operation of the call-registration means as the car is proceeding toward the predetermined position under the influence of said biasing control means, for causing said biasing control means to be ineffective to control said reversing means and for causing said 110 call-registration means to be effective to control said reversing means to cause it to move the car to the floor corresponding to a call registered.
14. In an elevator control system, motive means for moving an elevator car in a hatchway 115 past a plurality of floors, reversing means for starting and stopping said motive means, call-means at the floors and in the car, means operably responsive to the operation of the call-means for registering a plurality of calls and controlling 120 said reversing means to cause it to effect movement of the car to the floors corresponding to the calls registered, means movable in accordance with the movement of the car, deceleration means controlled by said call-registration means and said means movable in accordance with the movement of the car, operable to control said reversing means to cause it to stop the car at the floors for which calls have been registered, biasing control means operable when no calls are registered, for controlling said reversing 125 means to cause it to effect movement of the car toward a predetermined position, means for rendering said biasing control means ineffective until a predetermined time has expired after the 130 car stops in response to the last call registered, means including said means movable in accordance with the movement of the car, for rendering said biasing control means ineffective as the car approaches the predetermined position and 135 140 145 150

for rendering said deceleration means effective as the car approaches the predetermined position, whereby said car is stopped at the predetermined position, and means operably responsive to the operation of the call-registration means as the car is proceeding toward the predetermined position under the influence of said biasing control means, for causing said biasing control means to be ineffective to control said reversing means and for causing said call-registration means to be effective to control said reversing means to cause it to move the car to the floor corresponding to a call registered regardless of the location of the registered call with respect to the position of the car.

15. In an elevator control system, motive means for moving an elevator car in a hatchway past a plurality of floors, reversing means for starting and stopping said motive means, an 20 "up" call-means and a "down" call-means at each floor, means actuatable in response to the operation of said call-means for registering calls, means including said call-registration means, for 25 controlling said reversing means to cause it to effect the movement of the car in response to a plurality of "up" calls and "down" calls and to effect the stopping of the car only at the floors for which calls are registered corresponding in direction to the direction of movement of the car, 30 biasing control means, which is effective when no calls are registered, for controlling said reversing means to cause it to effect movement of the car toward a predetermined position, means including means movable in accordance with the movement of the car, for controlling said reversing means to cause it to effect the stopping of the car at the predetermined position, and means operably 35 responsive to the actuation of said call-registration means as the car is proceeding to the predetermined position under the influence of said independently controlling means, for causing said reversing means to be controlled by said call-registration means in preference to said independently controlling means regardless of the location of the registered call with respect to the car.

ceeding to the predetermined position under the influence of said biasing control means, for causing said reversing means to be controlled by said call-registration means in preference to said biasing control means regardless of the location 80 of the registered call with respect to the car.

16. In an elevator control system, motive means for moving an elevator car in a hatchway past a plurality of floors, reversing means for starting and stopping said motive means, an 85 "up" call-means and a "down" call-means at each floor, means actuatable in response to the operation of said call-means for registering calls, means including said call-registration means, for controlling said reversing means to cause it to effect the movement of the car in response to a plurality of "up" and "down" calls and to effect the stopping of the car only at the floors for which calls are registered corresponding in direction to the direction of movement of the car, 90 means effective when no calls are registered, for controlling said reversing means independently of said call-registration means to cause said reversing means to effect movement of the car toward a predetermined position, means including 95 100 means movable in accordance with the movement of the car, for controlling said reversing means to cause it to effect the stopping of the car at the predetermined position, and means operably responsive to the actuation of said call-registra- 105 tion means as the car is proceeding to the predetermined position under the influence of said independently controlling means, for causing said reversing means to be controlled by said call-registra- 110 tion means in preference to said independently controlling means regardless of the location of the registered call with respect to the car.
